UNITED STATES PATENT OFFICE

OSCAR J. MUTSCHEL, OF TOLEDO, OHIO, ASSIGNOR TO THE DE VILBISS COMPANY, OF
TOLEDO, OHIO, A CORPORATION OF OHIO

SPRAYING DEVICE

Application filed February 7, 1929. Serial No. 338,902.

This invention relates to a spraying device particularly adapted for spraying perfume and similar liquid preparations. A receptacle containing the perfume is preferably supported at the upper end of a standard, with the air pressure supply located within a hollow base on which the standard is mounted.

The general object of the invention is to provide a spraying device of the type described, which is attractive in appearance and which has novel and improved means for creating the air pressure by which the perfume or other preparation is discharged.

In its present form, this air pressure is supplied by a rubber bulb which is held within the hollow base and operatively connected by a passageway through the standard to the discharge nozzle connected with the top of the container. The base itself is rigid but is provided on its upper side with a depressible plunger having a head with a comparatively large surface engagable with the bulb to compress the same.

The invention in its present preferred embodiment will be more particularly described with reference to the accompanying drawing, the single figure of which represents a central vertical sectional view of the same.

As illustrated in the drawing, the hollow base is formed by an upper member 1 and a lower member 2 of pressed metal dished outwardly and secured together by any suitable method. One of the base members is formed with feet 3 constituting a stable support. A standard 4 extends upwardly from one side of the base, to which it may be secured in any suitable manner as by means of a threaded lower end 5 secured into a correspondingly threaded socket. In the present instance the standard is comprised of a number of sections, each having its upper end flared as shown at 6 and forming a socket in which the next succeeding section is welded or otherwise secured. The upper end of the standard is preferably in the form of a gooseneck 7, terminating in a spray head 8, from which a liquid receptacle 9 is supported in depending relation

thereto by means of a neck 10. The receptacle 9 may be made from any suitable material with a collar 20 secured to its top and having a threaded connection with the lower end of the neck 10. The spray head 8 is provided with a nozzle 11 to which is connected a liquid supply tube 12 leading from the bottom of the receptacle 9. The standard 4 is hollow or tubular and forms a passageway 13 through which air under pressure is supplied to the air discharge duct of the spray head 8. Nothing new is claimed for the spray head construction.

For supplying air under pressure through the passageway 13, the lower end of the standard 4 is provided with a nipple 14 which extends downwardly into the cavity within the base and has a rubber bulb 15 connected thereto. The bulb 15, when in its normal expanded condition, fills the greater portion of the cavity within the base. Directly above the bulb 15 and disposed centrally of the upper base member 1 is a plunger 16 which is guided for vertical movement in a collar 17 formed at the top of the base. When the bulb 15 is in its normal expanded condition the plunger 16 is held substantially in its uppermost position with its peripheral head flange 21 engaging the shoulder formed at the lower edge of the collar 17.

In the operation of the spraying device, the plunger 16 is depressed by the thumb or finger to compress the bulb 15 and force air under pressure through the passageway 13 and nozzle 11. This induces a flow of liquid through the liquid supply tube 12 and discharges it in the form of spray. The standard 4 is formed with a port 18, controlled by a check valve 19, to admit a fresh supply of air to the bulb 15 when the plunger 16 is released.

In connection with the invention, it will be noted that the liquid receptacle is supported at the upper end of the standard in depending relation thereto and that the air pressure supply is concealed within the basis and may be rendered operative merely by the depression of the plunger 16. This construction is particularly adapted to be embodied in perfumizers of attractive design,

to adorn a dressing table or the like. It is to be understood, however, that the shape and general arrangement of the various elements may be considerably modified without departing materially from the scope of the invention as defined in the claims.

What I claim is:

1. In a spraying device, a hollow base, a standard rising therefrom, a spray head supported by said standard, a liquid receptacle supported by said head, said standard having an air passageway therethrough operatively connected with said head, an air chamber housed within said base and connected to said passageway, and a plunger with its lower end housed within said base above the air chamber and compressible to compress said chamber and force air through said passageway. 75
2. In a spraying device, a base having a cavity therein, a standard rising from said base, a spray head supported by said standard, a liquid receptacle supported by said head, said standard having an air passageway therethrough operatively connected with said head, a self-expansible bulb housed within said cavity and connected to said passageway, and a plunger with its lower end housed within said cavity above the bulb and compressible to compress said bulb and thereby supply air under pressure through said passageway to said spray head. 80
3. In a spraying device, a hollow base, a standard rising from one side of the base, the upper end of said standard being turned inwardly toward the center line of the base and terminating in a spray head, a liquid receptacle operatively connected to said spray head, said standard having a passageway therethrough leading to said spray head a self-expansible bulb housed within said base and connected with said passageway, the upper wall of said base being inclined upwardly from its edge toward its center, and a vertically reciprocable plunger mounted substantially at the center of said upper wall with its lower end housed within said base and resting by gravity on said bulb, said plunger being compressible to compress said bulb and force air through said passageway to said spray head. 95
4. In a spraying device, a base having a cavity therein, a self-expansible bulb housed within said cavity, a standard rising from said base, a spray head supported by said standard, the lower end of said standard having a threaded connection with the base and provided with a reduced threaded extremity extending into said cavity and connected with the bulb, said standard having an air passageway therethrough connecting the bulb with the spray head, and a plunger with its lower end housed within said cavity above the bulb and compressible to compress 100
5. In a spraying device, a hollow base, a standard rising therefrom, a spray head supported by said standard, a liquid receptacle supported by said head, said standard having an air passageway therethrough operatively connected with said head, the bulb and thereby supply air under pressure through said passageway to the spray head. 105
6. In testimony whereof I have hereunto signed my name to this specification. 70
